SPRAY GUN

Hyman R. Rich, River Grove, Ill.

Application June 25, 1956, Serial No. 42,025

Term of patent 14 years

(Cl. D62—2)

Fig. 1.

Fig. 2.

Fig. 3.

Fig. 4.

Figure 1 is a side elevation of a spray gun showing my new design;

Figure 2 is a top plan view of the same;

Figure 3 is a left hand end view thereof; and

Figure 4 is a right hand end view thereof.

The dominant features of my design reside in the portions shown in full lines.

I claim:

The ornamental design for a spray gun, as shown and described.
